UNITED STATES PATENT OFFICE.

FRANK A. WILKES, OF MILWAUKEE, WISCONSIN, ASSIGNOR TO WISCONSIN BARREL & COOPERAGE CO., OF MILWAUKEE, WISCONSIN.

STAVE-TAPPING-OUT APPARATUS.

1,115,138.

Specification of Letters Patent.

Patented Oct. 27, 1914.

Application filed July 1, 1914. Serial No. 848,357.

To all whom it may concern:

Be it known that I, FRANK A. WILKES, a citizen of the United States, and resident of Milwaukee, in the county of Milwaukee and 5 State of Wisconsin, have invented certain new and useful Improvements in Stave-Tapping-Out Apparatus; and I do hereby declare that the following is a full, clear, and exact description thereof.

10 My invention refers to cooperage and has for its object to provide a simple, economical and effective means for shaping or finishing the assembled and hooped barrel staves by expanding the same uniformly to 15 effect a smooth outside circumference whereby the opposed edges of the group of staves are perfectly seamed and matched in circular formation, which staves, under ordinary conditions, lap each other irregularly if not 20 previously tapped out by hand, it being understood that to accomplish the desired result manual tapping out of the staves is now the method generally employed. The apparatus for accomplishing the desired result, as stated above, may be utilized as an 25 attachment to any type of barrel-trussing machine, wherein the gearing can be employed for transmitting the necessary power to the driven elements of my attachment, or 30 said apparatus may be designed as a unit, it being understood that any means within the knowledge of skilled mechanics for imparting motion to the working parts, is within the scope of my invention.

35 With the above objects in view the invention consists in certain peculiarities of construction and combination of mechanical elements as set forth hereinafter with reference to the accompanying illustrations and 40 subsequently claimed.

In the drawings Figure 1 represents a sectional elevation of a machine embodying the features of my invention, the section being indicated by line 1—1 of Fig. 2; Fig. 2, a 45 detailed cross-section of the same, the section being indicated by line 2—2 of Fig. 1, with parts broken away to more clearly illustrate certain details of construction, and Fig. 3, an enlarged sectional view of a head 50 constituting one of the elements of my invention showing an adjustable stave-receiving seat in detail.

Referring by characters to the drawings, 1, 1, indicate spindles which are mounted in 55 suitable boxes having wormed or threaded

ends 1', the threads on said ends being right and left. These spindles are arranged to be rotated synchronously by any desired driving gear, not shown. The companion threaded ends have mounted thereon followers 2, 2', which followers are in threaded engagement with the threaded ends of the spindles and are arranged to be thus drawn toward each other or retracted coincident to movement of the wormed spindles 60 in opposite directions. Extending through central apertures of the followers are plunger rods 3, 3', the rear ends of which plunger rods are also mounted in suitable bearings. The forward ends of the plunger 65 rods carry chucking disks 4, 4', which chucking disks constitute expander heads. The plunger-rods carry adjustable collars 5 to which ends of coiled springs 6, 6, are attached, the opposite ends of said springs being secured to the juxtaposed followers 2, 2'. Thus it will be observed that a yielding connection between the expander heads or 70 chucking disks and followers is effected through the springs, the tension of which 75 may be varied by adjusting the collars 5, 5'. As indicated in full lines in connection with the follower disk 2, a hooped setting head 7 is provided, which head is supported by guide-rods 8 that are in slidable union with 80 the follower board. The hoop-setting head 85 7 also carry pins 9 that extend through apertures with which the follower-board is provided and surrounding said pins are coiled springs 9', the same being interposed 90 between the follower-board and head 7, whereby a yielding connection is effected between these elements. The hoop-setting heads form no part of my invention and are of ordinary type having sets of hoop-engaging fingers 10, 10', that are arranged 95 to abut companion hoops A, A', at either end of a barrel and force the same to their correct position with relation to the assembled staves B. A pair of circular heads 100 11, 11, having central apertures therein are provided, which apertures are adapted to fit the plunger rods 3, 3', whereby the heads are in slidable union with said rods. Each head 11 is provided with a continuous series 105 of radially disposed slots 12 adjacent to its periphery, which slots receive retaining bolts 12', each of the same being in threaded union with an eared bracket 13. The feet of each of these brackets are rectangular in 110

form and are guided between parallel radially disposed flanges 14 that extend from the face of the head. Thus the brackets may be adjusted in or out with relation to the axis of the head and fixed in such adjustment to compensate for variations in the dimensions of barrels. Each head is also provided with a circular flange 15 adjacent to its periphery, which flange constitutes a stave-receiving seat. In order to provide for adjustment with relation to this seat, the outer face of the flange 15, as best shown in Fig. 3, is inwardly tapered for the reception of a removable ring 15', it being understood that a series of such rings may be provided of different outer diameters, whereby variations in the dimensions of the barrels at their ends may be compensated for. These removable rings 15', as shown, may be secured by countersunk bolts or screws 15''.

Mounted between the ears of each bracket is a radially disposed expansion block 16, the shank of which is pivoted to the bracket ears by a stud 17. Thus the expansion blocks are free to swing upon their pivots in a radial direction. The blocks, as shown, are provided with obliquely disposed cam faces 16', which faces are engaged by the chucking-disks 4, 4', respectively, whereby the blocks are expanded when the plunger rods 3 and 3' are moved toward each other where expansion blocks meet head to head as shown in Fig. 1, whereby each stave of the assemblage is subjected to positive pressure throughout its entire length.

In order to retract the two sets of expansion blocks, each block of the companion series is provided with a tappet-finger 16'' that extends radially from the shank of the block, as best shown in Fig. 1. Hence it is apparent that when the mandrels or chucking disks 4 and 4' are retracted their peripheral edges will engage the tappet-fingers and thus cause the corresponding series of blocks to be retracted or nested in circular form of a reduced diameter.

From the foregoing description it is manifest that, in operation, the unfinished barrel, comprising the assembled staves bound by their hoops, is placed in the position shown in Fig. 1, while the mechanism, comprising the head expansion blocks and chucking mandrels, is retracted to a position clear of the ends of the staves. The heads are then moved forward to the position shown in Fig. 1, whereby the ends of the assembled staves B are seated about the flange 15 or ring 15' so as to center the barrel. In this forward movement of the heads the expansion blocks are contracted, whereby they can readily be inserted within the partly finished barrel, in which position the chucking disks 4 and 4' are drawn toward the heads with their edges in engagement with the tappet fingers 16''. The threaded or worm-carry-

ing spindles 1, 1, are then revolved, whereby the followers 2 and 2' are caused to be drawn toward the ends of the barrel, carrying with them the plunger rods. This movement causes the periphery of the chucking disks to engage the cam faces 16' of the expansion blocks, whereby the companion sets or series of the same are expanded, the expansive force applied thereto being yieldable, through the spring connection between the follower boards and plunger rods. This movement of the chucking disks toward each other will thus exert a positive force upon the chucking blocks, whereby their working faces 18 will engage the inner faces of the series of irregularly lapped staves and expand the same to a perfect circle of the correct diameter to form the desired outside smooth and even surface upon the group of staves, the expansive force being opposed by the hoops. Thus the edges of the entire series are perfectly matched up to form smooth longitudinal seams, it being understood that the working faces 18 of the chucking blocks are slightly curved to form the desired contour of the inner face of the barrel.

While I have shown and described, as one exemplification of my invention, an apparatus embodying specific details particularly designed as an attachment to a barrel trussing machine, it should be understood that such details may be varied within the knowledge of skilled mechanics for accomplishing the desired result, without departing from the spirit of my invention.

I claim:

1. A stave tapping out apparatus comprising a pair of aligned spaced heads having annular stave-receiving seats, a series of pivoted radially disposed expansion blocks mounted upon each head adapted to enter the ends of an assemblage of barrel staves, and a yieldable reciprocative expander head engageable with each series of blocks whereby they are forced against said assemblage of staves.

2. A stave tapping out apparatus comprising a pair of slidable plunger-rods, followers connected to the plunger-rods, spindles in threaded union with the followers, heads in slidable union with the plunger rods having annular stave-receiving seats, a series of expansion blocks in pivotal union with each head, and chucking disks carried by said plunger-rods for engagement with the expansion blocks.

3. A stave tapping out apparatus comprising a pair of slidable plunger-rods, followers yieldably connected to the plunger-rods, spindles in threaded union with the followers, heads in slidable union with the plunger rods having annular stave-receiving seats, a series of expansion blocks in pivotal union with each head, and chucking disks

carried by said plunger-rods for engagement with the expansion blocks.

4. A stave tapping out apparatus comprising a pair of alined spaced heads having 5 adjustable annular stave-receiving seats, a series of radially disposed shiftable expansion blocks mounted upon each head adapted to enter the ends of an assemblage of barrel staves, and a reciprocal expander head 10 engageable with each series of blocks whereby they are forced against said assemblage of staves.

5. A stave tapping out apparatus comprising a pair of axially alined spaced heads 15 having annular stave-receiving seats, a series of radially disposed expansion blocks pivoted to each head, the expansion blocks being provided with obliquely disposed cam faces and tappet fingers, and reciprocal 20 chucking disks arranged to engage the cam faces and tappet fingers whereby the blocks are expanded and contracted.

6. A stave tapping out apparatus comprising a pair of rotatory spindles having

right and left threaded sections, followers 25 in threaded union with the companion threaded sections of the spindles, chucking disks carried by the followers, heads interposed between the disks and followers, and a series of expansion blocks carried by each 30 head engageable with the chucking disks.

7. A stave tapping out apparatus comprising a pair of alined spaced heads, a series of pivoted radially disposed expansion blocks mounted upon each head adapted to 35 enter the ends of an assemblage of barrel staves, and a yieldable reciprocal expander head engageable with each series of blocks whereby they are forced against said assemblage of staves.

In testimony that I claim the foregoing I have hereunto set my hand at Milwaukee in the county of Milwaukee and State of Wisconsin in the presence of two witnesses.

FRANK A. WILKES.
